(57) **CLAIM**

The ornamental design for a vehicle exterior, as shown and described.

DESCRIPTION

FIG. 1 is a front perspective view of a vehicle exterior showing our new design;

FIG. 2 is a rear perspective view thereof;

FIG. 3 is a side elevational view, the opposite side elevational view being a mirror image thereof;

FIG. 4 is a front elevational view thereof;

FIG. 5 is a rear elevational view thereof; and,

FIG. 6 is a top plan view thereof.

The broken line showings of the wheels, tires and front marquee are for illustrative purposes only and form no part of the claimed invention.
